(57) **CLAIM**

The ornamental design for a detector housing, as shown and described.

DESCRIPTION

FIG. 1 is an isometric view of an embodiment of a detector housing of the present disclosure;

FIG. 2 is a front view of an embodiment of a detector housing of the present disclosure;

FIG. 3 is a back view of an embodiment of a detector housing of the present disclosure;

FIG. 4 is a left side view of an embodiment of a detector housing of the present disclosure;

FIG. 5 is a right side view of an embodiment of a detector housing of the present disclosure;

FIG. 6 is a top view of an embodiment of a detector housing of the present disclosure; and,

FIG. 7 is a bottom view of an embodiment of a detector housing of the present disclosure.

The broken line showing of structural features is included for the purpose of illustrating non-claimed subject matter and forms no part of the claimed design.
